LOCK CONSTRUCTION

Walter E. Keller, Elkhart, Ind., assignor to The
Adlake Company, Chicago, Ill., a corporation of
Illinois

Application February 8, 1932, Serial No. 591,530

4 Claims. (Cl. 292—197)

This invention has to do with locks of the type used on railway car and motor bus window sash.

The principal object of the invention is to provide an improved lock which is characterized by the inclusion of a rack-engaging member of novel construction, arrangement and operation.

While the foregoing statement is indicative of the nature of the invention, other more specific objects and advantages will be apparent to those skilled in the art upon a full understanding of the parts which together constitute the improved lock.

A preferred embodiment of the invention is presented herein by way of illustration, but it will of course be appreciated that the invention is susceptible of embodiment in other structurally modified forms coming equally within the scope of the appended claims.

In the accompanying drawing:

Fig. 1 is a fragmentary face view of one corner of a sash equipped with the lock of the invention;

Fig. 2 is a horizontal section, taken on the line 2—2 of Fig. 1;

Fig. 3 is a vertical section taken on the line 3—3 of Fig. 1;

Fig. 4 is a vertical section taken on the irregular line 4—4 of Fig. 2; and

Fig. 5 is a view which corresponds to Fig. 4 but shows the rack-engaging member of the lock in its inoperative position.

Referring in detail to the drawing, it will be observed that the improved lock is shown as being mounted on one of the lower corners of a vertically movable car or bus window sash 10. The sash 10, which may be of any suitable construction, is positioned between an outer stop 11 and an inner stop 12, and the lock on the sash is adapted to coact with a lock rack 13 which faces toward the sash and is contained within a channel 14 which is formed in the inner stop 12. The rack 13, which may be of any suitable construction, contains a plurality of inclined seats 15 with which a pawl 16 on the sash is adapted to engage.

The pawl 16 is housed within a small vertically elongated rectangular casing 17, and the casing 17 is in turn set into a recess 18 in the edge of the sash, preferably flush with the latter, in which position it is secured by two or more screws 19. The side of the casing 17 which faces toward the rack 13 is open, whereby to permit the pawl 16 to operate through the same.

The pawl 16 is pivotally mounted at its upper end on a pin 20 which allows the pawl to swing in a vertical plane at right angles to the plane of the sash from a vertical position within the casing to an inclined position wherein the lower end or nose 21 of the pawl protrudes from the inner face of the sash and engages with any one of the seats 15 in the rack. The projected or inclined position of the pawl 16 is shown in Figs. 1, 2, 3 and 4, while the vertical or retracted position of the pawl is shown in Fig. 5.

The pawl 16 is operated by a bolt 22 which is slidably mounted in a horizontal guideway 23 in the bottom rail of the sash. The guideway 23 opens into the casing 17 through a passage 24 in the adjacent side wall of the latter and is urged in the direction of the pawl 16 by a coil spring 25 which is compressed between the rear end of the bolt and the rear end of the guideway. The bolt is adapted to be retracted against the action of the spring 25 by means of a finger piece 26 which extends into a hollowed out portion of a lock plate 27. The plate 27 is attached to the bottom rail of the sash by a number of screws 28 and is provided with a lift flange 29 in underlying relation to the exposed portion of the finger piece for coaction with the latter. The finger piece 26 is pivotally attached to the plate 27 at 30 and is provided with a stud 31 which extends laterally through an arcuate slot in the adjacent wall of the bottom rail into a vertically extending groove 32 in one side of the bolt 22, all as clearly shown in Fig. 2. The front end of the bolt is beveled as shown in Figs. 2, 3 and 4 to provide a rearwardly and downwardly inclined nose 33 for camming coaction with the back of the pawl 16.

When the finger piece 26 is depressed, as shown in Fig. 5, to withdraw the nose 33 from the pawl 16 against the yielding resistance of the spring 25, the pawl will be released and will swing down under its own weight into a vertical non-projecting position within the casing 17, free from engagement with any of the seats 15 in the rack 13, in which position of the pawl the sash may be easily raised or lowered in the guides. When the finger piece 26 is released, however, the spring 25 will project the nose 33 of the bolt against the adjacent back corner 34 of the pawl, which corner is preferably rounded off or beveled, and will cam the nose 21 of the pawl outwardly into wedged engagement with the rack, in vertically interlocking engagement with one of the seats 15 in the latter.

The angle at which the bolt 22 bears against

the pawl 16 in the fully projected position of the latter is preferably so slight as to prevent any force on the pawl in the opposite direction, no matter how great, from backing up the spring-pressed bolt, thereby producing an interlocking cooperation of the rack, pawl and bolt which effectively prevents the sash being raised from the outside. If desired, however, a more accentuated angle may be employed, sufficient to allow the sash to be raised by the application of a lifting force to the bottom rail without the necessity of even touching the finger piece 26.

The upper end 35 of the pawl is preferably rounded about the axis of the pin 20 and located closely adjacent to the top of the casing 17 in approximate contact with the under surface 36 of the latter, whereby to in some measure relieve the pin 20 from the severe end shocks to which the pawl is subjected when the sash is allowed to drop a little in being locked in a raised position. This additional back stop reinforcement for the pin will of course come into play more and more as wear develops between the pin and the pawl.

The casing 17 is preferably provided with an aperture 31 in opposition to the aperture 24, through which the bolt 22 may be withdrawn or inserted without necessitating removal of the casing 17.

Should the spring 25 break or become inoperative for any other reason, there is no danger of the sash dropping and causing injury, since the inclined position of the pawl 16, through the action of the weight of the sash thereon, will provide a stable support for the sash which is entirely independent of the action of the bolt 22. This inclined position of the pawl will also always maintain the sash tight against the outer stop 11 when the sash is being supported in any one of its raised positions.

To lower the sash 10 from any of these raised positions, it is merely necessary to depress the finger piece 26 and raise the sash just far enough to relieve the pressure on the bolt 16 and allow the latter to swing back into the casing 17.

The casing 17 may advantageously be provided

at its lower end with a projection 38 which extends beneath and interlocks vertically with the adjacent end of the sheet metal guideway 23 whereby to materially strengthen the entire lock assembly.

I claim:

1. The combination with a vertically movable sash, and a lock rack in opposition to the inside face of the same, of a pawl pivotally mounted on the sash for swinging movement into engagement with the rack, and a bolt slidably mounted on the sash at right angles to the direction of movement of the pawl for camming coaction with the latter.

2. The combination with a vertically movable sash, and a lock rack in opposition to the inside face of the sash, of a pawl pivotally mounted on the sash for swinging movement into engagement with the rack, and a spring-projected bolt slidably mounted on the sash at right angles to the direction of movement of the pawl for camming coaction with the latter, said bolt in its projected position engaging with the pawl at such an angle as to prevent return movement of the pawl.

3. The combination with a vertically movable sash, and a lock rack in opposition to the inside face of the sash, of a pawl pivotally mounted at its upper end on the sash with its lower end free to swing outwardly away from the inside face of the sash into engagement with the rack, and a spring-projected bolt slidably mounted on the sash at right angles to the direction of movement of the pawl and provided with a beveled nose for forcing the lower end of the pawl outwardly into engagement with the rack.

4. The combination with a vertically movable sash, and a lock rack in opposition to the inside face of the sash, of a pawl pivotally mounted on the sash for swinging movement into engagement with the rack, and a spring-projected bolt slidably mounted on the sash at right angles to the direction of movement of the pawl for camming coaction with the latter.

WALTER E. KELLER.
